ARTIFICIAL JACK-O'-LANTERN

Arthur J. Nelson, Milwaukee, Wis., assignor to
Pulp Reproduction Co., Milwaukee, Wis., a cor-
poration of Wisconsin

Application February 9, 1953, Serial No. 23,493

Term of patent 14 years

(Cl. D34—15)

To all whom it may concern:

Be it known that I, Arthur J. Nelson, a citizen of the United States, residing in the city of Milwaukee, in the county of Milwaukee and State of Wisconsin, have invented a new, original, and ornamental Design for an Artificial Jack-o'-Lantern, of which the following is a specification, reference being had to the accompanying drawing forming a part thereof.

In the drawing:

Fig. 1 is a side elevational view of an artificial jack-o'-lantern embodying my new design;

Fig. 2 is a front elevational view taken from the left of Fig. 1;

Fig. 3 is a rear elevational view taken from the right of Fig. 1; and

Fig. 4 is a top plan view of the lantern.

I claim:

The ornamental design for an artificial jack-o'-lantern, substantially as shown.

ARTHUR J. NELSON.
